poration of New York

Application February 26, 1954, Serial No. 412,908

2 Claims. (Cl. 179—2)

This invention pertains to signalling systems and apparatus, and has for its principal object the provision of an integrated sonic signalling system for use by marine craft as an aid to operation and navigation.

It is a more specific object of the invention to provide a combination of electrical apparatus having a multiplicity of different functions, all useful in the operation of marine or water-borne craft. Thus, the invention provides for electronic amplification of speech from the cabin, bridge or other control point of a craft, the amplified speech being projected from the craft by a suitable loudspeaker. This feature permits the operator to direct instructions, inquiries, warnings or the like to relatively remote points, without leaving his usual control position or station. Other boats, docks, bridge tenders and the like may be hailed easily and directly by the pilot or operator in his cabin.

The invention also provides for the reception and amplification of sounds external to the craft, so that answering hails, advice or the like may be heard readily by the operator at his station. The invention utilizes for this purpose the same transducer (loudspeaker) as a microphone, and since the latter is mounted outside the cabin or enclosure, it is able to pick up sounds from afar much more clearly than can the operator himself. The electronic amplification provided permits a further increase in range.

A further important object of the invention is to provide a system of the above type which is arranged to generate an audible tone, such as a whistle, which can be produced electronically under the control of the operator, for use as a signal, warning or the like, and which will therefore also be useful in place of the ordinary fog-horn. When operated at full power, and as a result of the amplification provided, such a signal has great carrying power, far beyond the range of a human voice. In accordance with the invention, the oscillations necessary for the production of such signals are readily and efficiently obtained by a switch-controlled modification in an amplifying channel, so that a minimum amount of additional equipment is required.

Still another important object of the invention is to provide a signal system of the above type which can be used as a sound-ranging signal, in connection with the signal receiving and amplifying system already referred to above. To this end, the apparatus is arranged so that immediately upon the production of a short blast of sound of a predetermined frequency, the receiving equipment is put in condition to receive the echo produced when the signal is reflected from another object (boat, pier, coastal building or the like), and means are provided for measuring the echo time to arrive at a figure indicative of the distance of such object. In connection with a loud-speaker (which operates also as a microphone) mounted for adjustment in azimuth, the apparatus provides for accurate information as to the position of the vessel relative to nearby visible or invisible objects, e.g., at night or in fog conditions.

2

The invention accomplishes the above objects by a compact and efficient combination of apparatus arranged to accomplish the desired functions with a minimum amount of equipment, for low cost, compactness of installation and low power drain. It has been found to be highly practical for small and medium sized vessels not ordinarily equipped with electronic signalling and navigational aids, and contributes in an important way to the ease, safety and enjoyment of the use of such craft, 10 whether by commercial operators or sportsmen.

The equipment may be powered from an ordinary alternating current power supply, if available on the vessel, but its power requirements are so light that it can equally well be energized from a six-volt storage battery or the like, with a suitable vibratory or motor-generator type of inverter. By the use of quick-heating filaments for the vacuum tubes employed, it is practical to design the apparatus so that the standby power is very low, yet the system is ready for immediate use when required.

20 The invention will now be described in connection with a specific and preferred embodiment thereof, it being understood that various modifications in the details thereof may be made without departing from the spirit or scope of the invention. Reference is now made to the 25 accompanying drawings, showing such a preferred embodiment, and in which:

Fig. 1 is a view in elevation showing the general installation of the novel system upon a marine vessel of moderate size,

30 Fig. 2 is a view, partially in block diagram form, showing the major electrical components of the equipment and their interconnections, and

Fig. 3 is a schematic wiring diagram showing the connections and controls for the complete system.

35 A thorough understanding of the invention will be aided by a brief recapitulation of the principal functions of the system:

(1) To enable the user to project his voice, amplified many times, to a remote place, and to enable him to listen to sounds outside the vessel, either in the form of speech, signals or range echoes.

40 (2) To enable the operator to produce and control an audible signal or tone, of large or selected amplitude, as a signal, warning or echo source.

(3) To enable the operator to establish the presence of 45 nearby objects, even though invisible, by the echo resulting from a signal generated as in (2) above, and to estimate its distance by timing the echo delay.

(4) If desired, to enable the operator to estimate the 50 direction of objects by controlling the orientation of his sound emitter and noting the effect on the amplitude of received sounds, such as echoes, or by listening to externally produced sounds such as from buoys or the like.

55 Referring now to Fig. 1 of the drawings, there is illustrated a marine craft or vessel 10 having a cabin or enclosure 12 in the forward or other portion of which an operator is stationed. At this position, he will normally be in position to control the engine and steering apparatus. At any desired external position, here shown as a forward position on the hull, there is mounted a combined loud-speaker and microphone or a sound pick-up 14, which may be a moving-coil dynamic speaker of known form. As shown, the speaker 14 is mounted for rotation in azimuth, as upon a post 16, and a pulley 18 is provided connected by a cable 20 to a wheel 22 within the cabin, so that the direction of maximum emission or sensitivity of the speaker may be adjusted at will. The wheel 22 is provided with proper indicia so that the direction of the speaker 14 relative to the longitudinal axis 60 of the boat may be determined. Within the cabin 12, and adjacent the operator's normal position, is placed the remainder of the apparatus constituting the invention,

here shown as a control box 24, an amplifier 26 and a power supply unit 28. Preferably these components are mounted adjacent one another upon a bulkhead or other support, but obviously the amplifier and power unit may be otherwise disposed if conditions necessitate.

As shown in Fig. 2, the amplifier unit is connected to the speaker 14 and to the power supply unit 28 shown as receiving electric energy from a battery 30. The amplifier unit is also connected to the control box 24 by a suitable cabling. The latter box carries a hand telephone 32 having the usual transmitter 34, preferably of the close-talking type (to avoid interference from engine noise and the like), a receiver 36, and a push-button switch 38 of the "push-to-talk" type. An on-off switch 40 enables the unit to be disconnected from the power source. On the front panel of control box 24 there is a function selector switch 42 to be described in detail below, and a pilot lamp 44 indicating when the equipment is turned on. A jack 46 permits a separate head telephone to be employed for listening purpose, where the operator wishes to have both hands free. A knob 48 operates a volume control potentiometer, to be described below.

The remaining item shown on control box 24 is a flasher lamp 50, used for timing the echoes received during distance ranging operations, in a manner to be described. Preferably, for convenience in installation and maintenance, the various major units of the equipment are connected by cables terminating in suitable plugs fitting corresponding sockets in the other units.

The manner in which the various functions and operations are carried out will best be understood by referring now to Fig. 3, in which all essential parts are shown with their interconnections in detail. As there shown, separate amplifiers are used for listening and for talking, and the latter is also employed as the oscillator for generating the signal tones. The pushbutton switch 38 of the handset is used not only to convert from "talk" condition to "listen" condition, when the selector switch 42 is in the talk-listen position, but it also controls the emission of the signal and ranging tones when the switch 42 is in "signal" and "range" positions. Switch 42 is shown in Fig. 3 as a five-position four-deck control, one position being provided for turning all power off. If a master switch such as 40 is provided (shown in both Figs. 2 and 3), this last position, to which the switch 42 is shown turned in Fig. 3, may be omitted.

Power circuits

A source of alternating current power is indicated in Fig. 3 by numeral 52, it being understood that this may be from any available source or may be derived from converter components in the power supply casing 28 of Fig. 2. The supply circuit passes through the primary winding of a power transformer 54 and thence to the first deck (A) of switch 42, where it is extended over the bridged contacts 56 through fuse 58 (and on-off switch 40) back to the supply line. This permits the on-off function to be performed either by the switch 40 or by the selector switch 42, as desired.

One secondary winding 60 of transformer 54 has one side grounded as at lead 62 and the other side connected to a conductor designated "Z" which terminates at the wiper of the second switch deck (B). The last three contacts of this deck are bridged and connected to a conductor "Y" which leads to the cathode heaters of amplifier tubes 64, 66, 68, 70 and 72, tubes 68 and 70 being shown as the two halves of a twin triode type. At level B of switch 42, therefore, provision is made for disabling the amplifier comprising those tubes, when the switch 42 is in the "talk" position; such amplifier is used only for listening purposes.

Another secondary winding 74 of transformer 54 has its high voltage terminals connected to the anodes of a full-wave rectifier tube 76, and its center-tap grounded

at lead 62, to provide a usual form of high voltage supply for the anodes of all of the vacuum tubes. The filament of rectifier 76 is energized by a third (low voltage) secondary winding 78, and is connected as at lead 80 to 5 provide the positive output voltage.

The anode supply voltage is smoothed in the usual way as by filter 82 and applied to a potentiometer 84 which supplies the desired anode voltage to lead 86.

A control relay 88 is used to convert the circuitry from 10 using the element 14 as a loud-speaker to operation thereof as a microphone or sound pick-up, and for other purposes. Its functions will be described in more detail below, but for the present it will be noted that its coil has one side connected to a lead "Z" connected to one side 15 of secondary winding 60. When push-to-talk (handset) button 38 is closed, a circuit is completed from secondary winding 60, the relay coil, the button 38 and ground to operate the relay contacts. When so operated, contact set *a* of the relay connects the anode supply from filter 20 82 over lead 89 to the anode circuits of the vacuum tubes 90, 92 and 94 of a combined amplifier-oscillator. The cathode heaters of these tubes are also energized by connection to the lead "Z."

"Listen" amplifier

The "Listen" amplifier, including tubes 64, 66, 68, 70 and 72 is used for amplifying sounds picked up by the speaker 14 and repeating them to the operator at the receiver 36 of the handset. It is to be energized whenever 30 the selector switch is in any of its last three positions, and hence the filament secondary through lead "Z" is connected (as mentioned above), in the last three positions of deck B of switch 42, to a common heater circuit lead "Y" leading to the heaters of these tubes. The signal input circuit for this amplifier may be traced from speaker 14 (now acting as a microphone) through the normally closed contact sets *c* and *d* of relay 88 to leads 35 96 and thence to input transformer 98. Tubes 64 and 66 form a conventional cascaded voltage amplifier, the 40 output of tube 66 being coupled to the grid-cathode circuit of the first triode 68 (shown as half of a twin triode) employed as an isolating cathode-follower stage feeding, by the common cathode resistor 100, the grid-cathode circuit of triode 70. A filter network 102 gives the amplifier 45 an emphasized characteristic in the voice frequency range, and the signal therefrom is conveyed to the output amplifier tube 72 feeding output transformer 104. One side of the secondary winding of the output transformer is connected to ground, the other side via lead 50 106 to the receiver 36 of the handset. In order to permit an auxiliary headset to be used (so that the operator's hands will be free during long listening period) a lead 108 connects the output of tube 72 also to the jack 46 into which either such a headset or even a small loudspeaker 55 may be plugged. When employed, the output to this speaker will be cut off by a short circuit to ground over contacts *b* of relay 88 whenever the push-to-talk button is operated. This prevents the acoustic output of the local speaker from feeding into the handset transmitter 60 34 at such times.

"Talk" amplifier

With the selector switch 42 in its second ("talk") position or third ("talk-listen") position, the "talk" amplifier will be energized. For clarity, the switch positions are referred to herein considering the position shown in Fig. 3 (off condition) as the first position, the others following in numerical order as the wipers are turned counter-clockwise. In the second position, deck A energizes the power transformer, deck B deenergizes the heaters of the listen amplifier, deck C interrupts a circuit which later supplies voltage to the flasher circuit (to be described), and deck D connects the transmitter 34 of the handset to the input transformer, over a lead 110. 70 Signals from the transmitter are thus conveyed to input 75

transformer 112 from which the volume control potentiometer 113 conveys the signal to the amplifier 90 and thence through coupling transformer 114 to a conventional push-pull output stage 92, 94 feeding output transformer 116. The secondary winding of the latter transformer has one side grounded, and the other connected to the normally open contact of contact set *c* of relay 88. The output circuit is therefore open until push-to-talk button 38 is closed, whereupon relay 88 operates and connects the signal lead from the transformer to the speaker 14 at contact set *c*, and of course grounds the other speaker terminal at contact set *d* to complete the talking circuit.

Tone signal oscillator

In the third position of switch 42, deck A completes the circuit supplying power transformer 54, deck B again supplies heater power to the listen amplifier, deck C continues to open the flasher supply circuit, and deck D reconnects the first stage circuit of the talk amplifier to act as a tone oscillator having a predetermined audible frequency tone output. This is accomplished by incorporating a feed-back circuit from the plate circuit of tube 90 to its input circuit via resistor 120, condenser 118, the wiper deck D and the primary winding of transformer 112. The tube 90 and its associated circuits now form an oscillator, preferably emitting a relatively low-pitched audio signal which, when amplified and conveyed to speaker 14 (as in the "talk" condition), will provide the equivalent of a horn or whistle signal for the vessel. Since the output is connected to speaker only when relay 88 is operated, the button 38 is used to turn the signal on and off.

Range signal operation

For the last operational condition, switch decks A and B make the same connections as before. Deck C, however, connects a high D.C. voltage from lead 86 via lead 122 and the switch wiper to a relaxation oscillator circuit comprising the flasher lamp 50, a similar lamp 124 employed as a voltage regulator, the condenser 126, and a pair of resistors 128 and 130. This circuit also includes in series the normally open contacts of a relay 131 whose coil is energized whenever the push-to-talk button 38 is depressed. The relay is of the slow-release type, so that, when energized by a momentary closure of switch 38, its contacts will close and remain closed for a period of the order of ten or fifteen seconds, and will then open again. While the relay 131 operates every time button 38 is depressed, the circuit for energizing the flasher lamp 50 will be completed only when the selector switch is in the range signal selecting condition.

The resistor 130 is adjustable to regulate the frequency of the flasher, being provided with a screw-driver or like adjustment for this purpose. Since the operation of this kind of relaxation oscillation is well known, a detailed description of the cycle of charge and discharge of the condenser, and illumination of lamp 50 thereby, is believed to be unnecessary. For the purpose of timing echoes, the frequency of the oscillator is preferably so set that the lamp 50 flashes 11 times each six seconds. The velocity of sound being taken at 1100 feet per second, the flash frequency will result in one flash for each hundred yards of travel time (one way) between the vessel and a reflecting object.

When the operator depresses button 38 momentarily, horn 14 will produce a short blast, and the contacts of relay 131 will close to start the flasher circuit. By noting the number of flashes which occur before receipt of an echo, the operator can readily estimate the distance to

the reflecting object; that is, each flash will correspond to 100 yards of such distance. The release time of relay 131 is selected so that the flashing will stop after a reasonable length of time which is longer than any expected echo time. A release time of ten second, for example, will permit the timing of echoes up to 1000 yards, and the operator will be advised as to when a new measurement may be made, because the flasher will stop operating when relay 131 releases and until button 38 is operated to repeat the measuring process.

- The relatively low signal tone produced by the oscillator-amplifier tube 90 stage is not too well suited for sound ranging purposes. It is low and may be confused with other signals. A higher pitch tone would be preferable. Therefore, as shown, an auxiliary condenser 132 is connected in series with the oscillator condenser 118 by switch deck D when set in its range position, this serving to raise the pitch of the signal tone to a penetrating high value.
- It will be seen from the above description that all of the objects of the invention are satisfied by the disclosed apparatus in a compact and efficient manner. Necessary interconnections of a minimum number of components are made quickly and automatically under control of a single selector switch, and conversion from talk to listen and signal functions is accomplished readily by the operator using button 38 in a natural and simple way. Obviously, however, the invention could be carried out by modified apparatus, and such modifications as fall within the spirit of the invention are intended to be included within the scope of the appended claims.

What is claimed is:

1. Audible signalling apparatus for marine craft and the like, comprising a transducer constituting a combined loudspeaker and microphone, a telephone having a transmitter and a receiver, a first amplifier for amplifying the output of said telephone transmitter, a second amplifier for amplifying the output of said transducer when used as a microphone, a relay operable to connect said transducer selectively to the input of said second amplifier and to the output of said first amplifier, a switch at said telephone for operating said relay, a selector switch to disable said second amplifier, means including a feedback circuit controlled by said selector switch whereby said first amplifier may be operated selectively as a signal oscillator, means for connecting said telephone receiver to the output of said second amplifier, and means for connecting said telephone transmitter to the input of said first amplifier.
2. Audible signalling apparatus as set forth in claim 1, including means controlled by said selector switch for modifying said feedback circuit to alter the frequency of oscillation to a different value.
